UNITED STATES PATENT OFFICE

WALTER EVERETT MOLINS, OF DEPTFORD, LONDON, ENGLAND

CIGARETTE MACHINERY

Application filed February 8, 1930, Serial No. 427,073, and in Great Britain December 27, 1928.

This invention is for improvements in or relating to cigarette machinery, and more particularly to a device of the type which receives cigarettes from the mechanism which severs the cigarette rod into lengths and deposits the same upon a conveyor movable in the direction transverse to the direction of movement of the cigarette rod.

The object of the present invention is to provide a device which will receive the cigarettes from the said cutting mechanism and deposit them substantially in the same position upon a transversely moving conveyor independent of the speed at which the cigarette machine is operating.

It is found in practice in high speed cigarette making machines of the continuous rod type that when the machine is started or stopped the cigarette rod is moving at a substantially slower speed than when it is normally operating, and due to the fact that the cigarettes are delivered at a slower speed, the device usually employed for moving them on to a transverse conveyor very often damages the cigarettes, or the mechanism becomes choked, thus necessitating clearing the machine of obstruction with the consequent loss of time.

The present invention comprises a device of the type referred to wherein the successive cigarettes as they are severed from the rod are received by a conveyor operable to travel faster than the axial speed of the rod, and deliver the cigarettes to a transverse conveyor and arranged so that the point of discharge of the cigarettes from the conveyor is dependent upon the axial speed of the cigarettes.

In a preferred form the invention comprises a device of the type referred to wherein the successive cigarettes as they are severed from the rod are received by a conveyor operable to travel faster than the axial speed of the rod and arranged so that the free end thereof dips downwardly towards

the transverse conveyor at a point sufficiently far from the remote edge of said transfer conveyor so that when the cigarettes are delivered at the normal speed of the machine they will be discharged from the said conveyor substantially at the point where the same commences to dip downwardly, whereas when the cigarettes are delivered at a speed slower than the normal speed of the rod, the cigarettes will be carried a distance down the sloping portion of the conveyor dependent upon the speed of the cigarettes, and deposited at substantially the same point upon the transverse conveyor.

The invention will be more particularly described with reference to the accompanying drawing, in which:

Fig. 1 is a plan view of a portion of the receiving apparatus of a continuous rod cigarette machine.

Fig. 2 is a view of the apparatus as seen in direction of arrow "A", Fig. 1.

Fig. 3 is a view of the apparatus as seen in direction of arrow "B", Fig. 2.

Referring to the drawing, the cigarettes 1 are received by a band 2 from the cutting apparatus (not shown). The band 2 is arranged to travel at a linear speed which is greater than the axial speed of the cigarette rod so that as the cigarettes are received by the band from the cutting mechanism the same will be separated from one another by a substantial amount. The conveyor band 2 is preferably arranged to move horizontally for the major portion of its length until it passes over an adjustable guide 3 which causes it to dip downwardly towards the surface of the transversely moving conveyor band 4.

A deflector 5 is adjustably fixed above the conveyor band 4 and is curved as shown so as to arrest the motion of the cigarettes and cause them to be deposited on the band. The deflector 5 is so shaped that when a cigarette slides down it on to the band, the rear

end of said cigarette first comes into contact with the transverse band so that the cigarette is swung around and all the cigarettes are then deposited on the band evenly and 5 square thereto as shown in Fig. 1.

With a device of this character it is found that the cigarettes when travelling at the normal speed of the cigarette machine, for example twelve hundred cigarettes per minute, 10 leave the band under their own inertia when they arrive at that portion thereof which dips towards the transversely moving conveyor, and drop by means of gravity on to the said conveyor without impinging against the 15 usual side wall which is mounted at the free edge of the said transversely moving conveyor.

When the cigarette machine is stopped, or 20 the speed of the rod reduced for any reason, it is found that the cigarettes are still separated from one another, but due to the reduction in speed, the cigarettes will not leave the band where the same dips downwardly 25 towards the transversely moving conveyor, but will move along the said dipping portion of the band and leave the same at a point dependent upon the axial speed of the cigarette, and will be deposited in substantially 30 the same position upon the transversely moving band as is the case when the cigarettes are moving at a high speed.

It will be appreciated that with a device 35 of the above character, the cigarettes may be deposited, without injury, upon a transversely moving conveyor, and in the case where cork tipped cigarettes have to be separated into two rows, a separator may be mounted above the band hereinbefore referred to so 40 as to remove each alternate cigarette therefrom and permit the remaining cigarettes to be deposited in the manner hereinbefore described.

Any suitable device may be employed for 45 removing each alternate cigarette from the band, for example a rotary vane as described in specification Serial No. 272,997.

Thus it will be seen that according to this 50 invention a cigarette separating device is provided which will operate throughout the entire speed range of the machine and deposit the cigarettes on the transverse conveyor without damage.

What I claim as my invention and desire 55 to secure by Letters Patent is:—

1. In a device for conveying cigarettes after their severance from a moving cigarette rod, the combination with a conveyor normally travelling faster than the rod for receiving the severed cigarettes, conveying the 60 same in spaced relation in the direction of their length, and delivering the same at a fixed point when moving slowly, of means for causing said conveyor to dip in advance of said fixed point whereby fast operation of 65 said conveyor causes the cigarettes to leave

the conveyor at the point of dip and to be projected to the fixed point of delivery.

2. In a device for conveying cigarettes after their severance from a moving cigarette rod, the combination with a conveyor 70 normally travelling faster than the rod for receiving the severed cigarettes, conveying the same in spaced relation in the direction of their length, and delivering the same at a fixed point when moving slowly, of means 75 for causing said conveyor to dip in advance of said fixed point whereby fast operation of said conveyor causes the cigarettes to leave the conveyor at the point of dip and to be projected to the fixed point of delivery, and 80 a second conveyor disposed substantially at right angles to the first conveyor and intersecting the point of delivery.

3. In apparatus of the class described, the combination with a conveyor arranged to receive cigarettes, convey the same in spaced relation in the direction of their length, and deliver the same at a given point when moving slowly, of a second conveyor travelling substantially at right angles to said first conveyor for receiving the cigarettes at said point of delivery and conveying them in spaced parallel relation, said first conveyor dipping at a point in advance of the said delivery point whereby operation of said first 95 conveyor at high speed will cause the projection of the cigarettes from the point of dip to the delivery point.

4. In apparatus of the class described, the combination with a conveyor for receiving cigarettes and conveying the same in the direction of their length, of a second conveyor moving substantially at right angles to said first conveyor for receiving cigarettes from the delivery end of the first conveyor, and means disposed adjacent the delivery end of the first conveyor and over the second conveyor 100 having a surface inclined away from said first conveyor in the direction of movement of said second conveyor and positioned to be engaged by the forward end of the discharging cigarettes to retard the motion of the latter, whereby the rearward end of each cigarette first falls upon the second conveyor to effect their disposal thereon in parallel 105 relation to their first direction of movement.

5. In apparatus of the class described, the combination with a conveyor for receiving cigarettes and conveying the same in the direction of their length, of a second conveyor moving substantially at right angles to said first conveyor for receiving cigarettes from the delivery end of the first conveyor, means whereby said first conveyor dips in advance 110 of said delivery end to cause projection of the cigarettes to the delivery point when the conveyor is moving rapidly, and means disposed adjacent the delivery end of the first conveyor and over the second conveyor having a surface inclined away from said first 115 conveyor.

veyor in the direction of movement of said second conveyor and positioned to be engaged by the forward end of the discharging cigarettes to retard the motion of the latter, 5 whereby the rearward end of each cigarette first falls upon the second conveyor to effect their disposal thereon in parallel relation to their first direction of movement.

In testimony whereof I hereunto affix my
10 signature.

WALTER EVERETT MOLINS.
